COMBINED WINDOW SHADE AND AWNING

Filed Oct. 25, 1926

UNITED STATES PATENT OFFICE.

THOMAS H. CHANDLER, OF LAWRENCE, KANSAS.

COMBINED WINDOW SHADE AND AWNING.

Application filed October 25, 1926. Serial No. 143,911.

My invention relates to improvements in combined window shades and awnings. It is particularly well adapted for use in connection with windows in the doors or bodies 5 of an automobile.

One of the objects of my invention is to provide a window shade and awning of the kind described which is simple, cheap, durable, not liable to get out of order, which can 10 readily be applied to existing windows, which can be used as an awning which projects outside the window, or which can be raised or lowered in the manner of an ordinary window shade, and which has novel means for 15 being releasably held in the positions to which it may be adjusted.

The novel features of my invention are hereinafter fully described and claimed.

In the accompanying drawing, which illustrates the preferred embodiment of my invention,

Fig. 1 is an inside elevation of my improved window shade and awning shown mounted in a window frame.

Fig. 2 is a vertical sectional view of the same.

Fig. 3 is a vertical sectional view of the same, showing the sheet in solid lines partly extended, and in dotted lines fully extended, 30 a portion of the window being broken away.

Fig. 4 is an enlarged vertical longitudinal sectional view of one end portion of the roller and parts connected therewith.

Fig. 5 is an enlarged vertical sectional view 35 of a portion of one of the arms of the U shaped member, the rotary member with which it co-operates and parts connected with the rotary member.

Fig. 6 is a horizontal section of what is 40 shown in Fig. 5.

Similar reference characters designate similar parts in the different views.

1 designates a horizontal rotary roller having fastened centrally to it at one of its ends 45 a rotary pivot member 2, and having mounted in its other end a stationary pivot member 3 on which the roller 1 is rotatable.

In the end of the roller containing the pivot member 3 is a recess 4 in which is mounted a longitudinal coil spring 5 one end of which is fastened to the roller 1 and the other end of which is fastened to the pivot member 3. The spring 5 serves to retract the roller 1 so as to wind on the latter a sheet 6, which serves 55 as an awning sheet or a shade, and which has

one end portion fastened to and adapted to be wound on the roller 1 by the spring 5.

The other end of the sheet 6 is fastened to a stretcher member comprising a U shaped member 7, the arms 8, of which, are respectively longitudinally slidably mounted in two holes 9 respectively provided in two rotary horizontal members 10, which are respectively rotatably mounted by a swivel connection in two hollow bosses 11 respectively provided at the inner sides of two vertical plates 12 and 13, which are adapted to be respectively fastened, as by screws 14, to the inner sides of the jambs of a window frame 15 of a door or body of an automobile.

The pivot member 2 is rotatable in a hole provided therefor in the plate 12. The stationary pivot member 3 is of a shape other than circular in cross section. In the drawing it is rectangular in cross section and 70 is fitted in a hole of corresponding shape, so that it may be held from turning.

Respectively fitted in threaded horizontal holes provided in the inner ends of the rotary members 10 are two screws 16, which are 80 adapted to be turned so as to respectively bear against the arms 8 of the U shaped member, and to force the latter into holding engagement respectively with the bosses 11, the holes 9 in said rotary members 10 being of such 85 dimensions and disposition as to permit of such holding engagement.

When the roller 1 is located closely adjacent to the inner upper part of the window frame 15, and the rotary members 10 are 90 disposed at substantially the middle of the length of the frame 15, the sheet 6 may be disposed, when operated as a shade, so as to cover any portion of the window glass, designated by 17, or to cover the glass for substantially the entire length thereof. It will be noted that the plates 12 and 13, which carry the roller 1 and the rotary members 10, are located, as are the roller 1 and rotary members 10, wholly at one side, the inner 100 side, of the glass 17, whereby, when the U-shaped member has its transverse portion 7 and arms 8 swung to the inner side of the glass 17, as shown in Fig. 2, the glass 17 may be slid to the fully closed position, shown 105 in Fig. 2, and the U-shaped member may be swung to the position shown in dotted lines in Fig. 2, in which position the sheet 6 will fully cover the glass for the length thereof.

When it is desired to use the sheet 6 as a 110

shade for covering the upper half or a portion thereof of the glass 17, the sheet 6 is pulled straight downwardly to the desired position, as for example, to the position shown in dotted lines in Fig. 1, after which the screws 16 are tightened, thus holding the arms clamped to the bosses 11.

If it is desired to cover the entire glass 17, the arms 8 are swung inwardly and downwardly, at their upper ends, to the position shown in dotted lines in Fig. 2, in which position the transverse portion 7 of the U shaped member will have crossed the vertical plane of the axes of the members 10, and, the screws 16 being then tightened, the arms 8 will retain the sheet 6 in this extended position, due to the tension of the spring 5.

If it is desired to cover but a portion of the glass 17 below the members 10, the screws 16 may be loosened, and the spring 5 be permitted to rotate the roller 1 so as to draw upwardly the sheet 6 until the desired position is reached, at which time the screws 16 are tightened to hold the arms 8 in the adjusted position.

As will be noted, the rotary members 10 are disposed at such distance below the roller 1 that they will engage the arms 8 closely adjacent to the lower ends thereof, when the sheet 6 has been wound to its limit on the roller 1. This enables the adjustment of the sheet 6 as a shade to the positions hereinbefore described.

When the sheet 6 is to be used as an awning sheet at the outer side of the window, the glass 17 is lowered, as in Fig. 3, and the

arms 8 are swung outwardly to the desired angle, and the screws 16 tightened. The arms 8 may be swung, within their range of movement, to any desired outwardly and upwardly or outwardly and downwardly inclined position. Two positions of the arms 8 are shown respectively in solid and dotted lines in Fig. 3, with the sheet 6 being used as an awning sheet. Upon loosening the screws 16, the arms 8 may be longitudinally adjusted, inwardly or outwardly, to any desired position, and to permit of any desired angle of the sheet 6.

I do not limit my invention to the structure shown and described, as many modifications, within the scope of the appended claim, may be made without departing from the spirit of my invention.

What I claim is:—

In a combined window shade and awning comprising a spring retracted roller, a stretcher member, and a sheet having its ends respectively attached to the roller and to said stretcher member; a rotary member having a hole transverse to its axis adapted to have said stretcher member slidably mounted therein, a set screw in said rotary member adapted to releasably engage and hold said stretcher member from longitudinal movement in said hole, and means rotatably supporting said member with the axis of the latter parallel with the axis of said roller.

In testimony whereof I have signed my name to this specification.

THOMAS H. CHANDLER.
